UNITED STATES PATENT OFFICE

PIERRE LATECOÈRE, OF PARIS, FRANCE

AIRPLANE

Application filed December 11, 1930, Serial No. 501,706, and in Belgium December 21, 1929.

The present invention relates to airplanes and more particularly, to hydroplanes.

One of the problems in hydroplane design, is to provide means easily operable to detach the wings when the plane has alighted on the water because of an accident or otherwise, whereby a floating unit including the motor remains which is capable of being towed through a heavy sea and without the interfering effect of wind resistance exerted on the wings.

Hitherto, detachment of the wings has been effected by loosening appropriate bolts or other fastening devices. Systems have been devised in which the wings may be simultaneously detached on both sides of the plane by a single maneuver of a central control mechanism. But in such systems, it has been found that a considerable expenditure of force is necessary and that the central operating mechanism frequently jammed.

One of the objects of the present invention is to eliminate danger of jamming and diminish the effort to be exerted on the central releasing mechanism. This is accomplished by providing a first group releasable means capable of taking wing strains produced during flight, and a second group of means designed to sustain the weight of the wings, whereby when the first group of means is loosened, the second group of means may be easily actuated by a central control mechanism to detach the wings from the rest of the hydroplane.

Further objects will appear in the course of the detailed description now to be given with reference to the accompanying drawings, in which:

Figs. 1 to 6 show, diagrammatically, different forms of hydroplane assemblies to which the invention may be applied;

Fig. 7 is a perspective of the releasing assembly;

Fig. 8 shows an assembly capable of being mounted on certain forms of hydroplanes and capable of detaching the struts and similar structures from the floating portions.

Referring to the various figures in the drawings, there is shown a variety of types of hydroplane assemblies composed of the

following elements: a boat or floatable central portion *a* (Figs. 1, 2 and 3) provided with auxiliary floats *c* (Figs. 1 and 3), if desired; a fuselage *b* (struts *g* for monoplanes of the types shown in the Figs. 2 and 5); (means for detaching the struts *g* when used from the floating portions of the hydroplane comprising a pivotally mounted tubular member *i* terminating in a sloping portion *h* adapted to co-act with a correspondingly formed surface on the free end of struts *g*, and a turn buckle *f* threadedly engaging with element *i* and slidably abutting against a flange formed on element *g*); and pairs of combined means for sustaining the weight of the wings and resisting the strains on the latter during flight consisting of (Fig. 7) longérons *j*¹ extending longitudinally along the wings, intermediate longérons *j*² forming part of the bolt or central floating and sustaining assembly and interposed between aligned pairs of longérons *j*¹, elements *j*¹ and *j*² being provided with male and female portions of the mortice and tenon or tongue and groove types, a bolt *e* traversing the male and female portions of *j*¹ and *j*², a rod and turn buckle assembly *k* pivotally connected to *j*¹ and provided with a looped portion *l* at one extremity, a hook *m* pivotally mounted on *j*², and adapted to co-act with looped portion *l*, a trigger *n* pivotally connected to *j*² and maintaining hook *m* inside looped portion *l*, a Bowden wire *p* adapted to actuate trigger *n* and a lever *q* operable to actuate one or several, Bowden elements *p*.

Eight elements of the type shown in Fig. 7 are mounted in pairs at points AA', BB', CC' and DD'. Where struts of the type *g* shown in the Figs. 2 and 5 are employed, the latter may be either (1) made up in one piece and detached from the central assembly by releasing combination CC' and DD' of the type shown in Fig. 7 or (2) made up in two pieces as shown in Fig. 8, in which case releasing mechanisms CC' and DD' may be dispensed with, combinations AA' and BB' being operable to release the wings in two steps after turnbuckles *f* have been operated to release the struts.

The hereinabove described assembly is operated in the following manner: Assuming that the hydroplane has alighted on the water, bolts *e* are first removed, then lever *q* is operated to actuate all of the Bowden wires so as to simultaneously move all of triggers *n* out of engagement with hooks *m*; the latter will then slide out of loops *l* and release turn buckle assemblies *k*; the wings are then free to drop away from the floating portion of the hydroplane.

It is to be emphasized that bolts *e* serve to take the strains on the wings during flight, while turn buckle assemblies *k* are designed as to strength to merely support the weight of the wings after bolts *e* have been removed.

What I claim is:—

1. In a composite heavier-than-air machine provided with a central portion including a motor, and a pair of detachable wings, a compound assembly for detachably supporting said wings on said central portion comprising a first plurality of means connecting said wings to said central portion, said first plurality of means being operative to release said wings from said central portion, and a second plurality of means capable of retaining the wings in flight position when said first plurality of means has been operated to release the wings, each of said second plurality of means including a tie element extending from a wing to the central portion, and means for releasing said tie element.

2. In a composite heavier-than-air machine provided with a central portion including a motor, and a pair of detachable wings, a compound assembly for detachably supporting said wings on said central portion comprising a first plurality of means connecting said wings to said central portion, said first plurality of means being operative to release said wings from said central portion, and a second plurality of means capable of retaining the wings in flight position when said first plurality of means has been operated to release the wings from the central portion, each of said second plurality of means including a tie element extending from a wing to the central portion, said tie element having a loop formed on one end thereof, a hook engageable with said loop, and means for releasing said hook from said loop.

3. In a composite heavier-than-air machine provided with a central portion including a motor, and a pair of detachable wings, means for detachably supporting said wings on said central portion comprising a first plurality of means connecting said wings to said central portion, said first plurality of means being operable to release said wings from said central portion, a second plurality of means capable of retaining the wings in flight position when said first group of means has been operated to release said wings from

the central portion, said second plurality of means including a tie element pivotally connected to one of the wings and having a loop formed at one extremity thereof, a hook mounted on the central portion and positioned to engage in the loop of the tie element, and means for releasing said hook from said loop.

4. A structure as defined in claim 7 in combination with a pair of struts supporting said wings, said struts being formed in at least two sections, and means for detaching one of said sections from the other.

5. A structure as defined in claim 7 in combination with a pair of struts positioned to sustain said wings, said struts being formed in at least two sections, one of said sections having a threaded portion formed thereon, and threaded means engaging with said threaded portion and operative to connect said sections to, and to detach said sections from, one another.

6. In a composite heavier-than-air machine, a floatable central portion, a pair of wings, and an arrangement for supporting said wings detachably on said central portion, said arrangement including a first group of means designed and dimensioned to withstand strains occurring during flight and landing and a second group of means capable of retaining the wings in flight position and incapable of sustaining flight loads, either of said means being capable of holding the wings to the body independently of the condition of the other means.

7. In a composite heavier-than-air machine provided with a central floatable portion, a pair of wings, and an arrangement for detachably supporting said wings on said central portion comprising a first group of means connecting said wings to said central portion, said first group of means being dimensioned to withstand strains occurring during flight, a second group of means capable of retaining the wings in flight position when said first group of means has been operated to disconnect said wings from the central portion, and means operative to actuate said second group of means to release said wings from the central portion.

8. In a composite heavier-than-air machine provided with a central floatable portion, a pair of wings, and an arrangement for detachably supporting said wings on said central portion comprising a first group of means connecting said wings to said central portion, said first group of means being dimensioned to withstand strains occurring during flight, a second group of means capable of retaining the wings in flight position when said first group of means has been operated to disconnect said wings from the central portion, and means operative to actuate said second group of means to release all

said wings simultaneously from said central portion.

9. In a machine as claimed in claim 7, said second group of means including releasable tie elements connecting said wings to said central portion.

In testimony whereof I affix my signature.

PIERRE LATÉCOÈRE.
